UNITED STATES PATENT OFFICE.

EDGAR KIDWELL, OF WASHINGTON, DISTRICT OF COLUMBIA, ASSIGNOR TO WASTE UTILITIES COMPANY, OF NEW YORK, N. Y., A CORPORATION OF DELAWARE.

FURNACE FOR LOW-GRADE COMBUSTIBLES.

1,184,351.

Specification of Letters Patent. Patented May 23, 1916.

Application filed October 23, 1912. Serial No. 727,310.

To all whom it may concern:

Be it known that I, EDGAR KIDWELL, a resident of Washington, in the District of Columbia, have invented a new and useful 5 Furnace for Low-Grade Combustibles, of which the following is a full, clear, and exact description, reference being had to the accompanying drawings, forming part of this specification, in which—
10 Figure 1 is a central vertical section showing one form of furnace constructed in accordance with my invention; Fig. 2 is a similar view showing a modification, and Fig. 3 is a detail view showing a modified 15 form of baffle.

My invention relates to the class of furnaces for burning garbage or low-grade fuels, and particularly to that type wherein the material is brought to a slag condition 20 on an upper grate and then dropped on a lower grate, where it is used for heating air passing to the upper grate. In such furnaces there is a great danger of warping and destroying the upper grate, owing to its 25 direct exposure to the radiant heat from the fuel on the lower grate.

My invention is designed to overcome this difficulty, and it consists in providing a protecting baffle or partition between the upper 30 and lower grates while at the same time allowing the fuel to be dropped from the upper to the lower grate. This dropping down of the charge may be accomplished either by having a movable baffle or barrier 35 between the two grates, or by having a barrier with a passage around it through which the charge may feed down.

In the drawings, referring to Fig. 1, 2 represents the shell and lining of a cupola-shaped garbage destructor, into which the 40 charges of garbage are fed through the top opening 3. These charges fall upon a grate 4, which is of any desired or usual form. In addition to the air supplied from the lower 45 chamber up through this upper grate, air under pressure may be supplied to cavities in said head itself as in the Fried system. This grate 4 is carried on suitable guides, on which it slides horizontally, and below it 50 is shown refractory transverse partition or baffle 5, these two sliding elements being connected to a cross-head 6 actuated from hydraulic cylinder 7. The lower grate 8 is also preferably a horizontally sliding grate, 55 so that after the air has been heated by the

charges dropped thereon, these charges may be dropped through the hopper-shaped bottom 9 into the car 10. I have shown the grate 8 as also actuated by suitable connections with the hydraulic cylinder 11. 60

Air is fed in through pipe 12, having a control valve indicated at 13, this air entering below the lower grate 8. The air passing up through the slagged material on the lower grate becomes heated, and is then 65 fed to the fuel on the upper grate in any desirable way. In this figure it passes through a by-pass flue 14; though it may pass directly through inclined holes or perforations in the refractory baffle 5 as shown 70 in Fig. 3. In this case the inclination would serve to prevent radiant heat acting upon the upper grate.

In the use of the apparatus, the charges are dumped upon the upper grate, and 75 burned and slagged thereon, the air being supplied to this grate from one source, and hot air also passing up to it from the lower grate. When the charge is slagged, the hydraulic cylinder is actuated to pull out 80 both the upper grate and the baffle, whereupon the charge falls upon the lower grate. The upper grate and baffle are then restored to position, another charge is fed on the upper grate, and the operation goes on as 85 before, the charges being dropped from the lower grate at suitable intervals.

In Fig. 2 I show a form similar to that of Fig. 1, except that the baffle 5^a is stationary and takes the form of a horizontally 90 extending hollow ridge of suitable refractory material. In this case the material drops down from the upper grate upon the inclined ledge 15, and slides down through the opening 16 and thence back onto the lower grate. The hot air from the lower 95 grate may also pass up through this opening 16.

The advantages of my invention result from the protection afforded to the upper 100 of the two grates of a furnace for burning low-grade fuels where there is a slagging action and where the slagged material is held on a lower grate for the purpose of heating air passing through the fresh fuel 105 on the upper grate.

The invention makes the furnace long-lived, greatly decreases repairs, and is believed to be essential in furnaces of this 110 type.

Many variations may be made in the form and arrangement of the furnace, the grates, the air supply, &c., without departing from my invention.

5 I claim:—

1. In a furnace of low grade combustibles, the combination of superimposed grates, a refractory baffle arranged to cut off the radiant heat from the lower grate to the upper 25 grate, and means for directing the gases from the lower grate to the space below the upper grate; substantially as described.

10 2. In a furnace for low grade combustibles, the combination of superimposed grates, a refractory baffle arranged to cut off the radiant heat from the lower grate to the upper grate, means for directing the gases from the lower grate to a space below the upper grate, and means for dumping the material from the upper grate onto the lower grate; substantially as described.

15 3. In a furnace for low grade combustibles, the combination of superimposed

grates, a refractory baffle arranged to cut off the radiant heat from the lower grate 25 to the upper grate, a passage arranged to conduct the gases arising from the lower grate to the space below the upper grate, and mechanism for moving the upper grate to dump the material therefrom upon the 30 lower grate; substantially as described.

4. A furnace for low grade combustibles having a movable main grate, a lower grate, a movable refractory baffle between said grates, and mechanism for moving the baffle and main grate in timed relation to each other to allow the material to be dumped directly from the main grate onto the lower grate, substantially as described. 35

In testimony whereof, I have hereunto set 40 my hand.

EDGAR KIDWELL.
